UNITED STATES PATENT OFFICE.

JOSEPH LOEWENTHAL, OF NEWARK, NEW JERSEY.

REVERSIBLE COAT.

SPECIFICATION forming part of Letters Patent No. 340,885, dated April 27, 1886.

Application filed July 2, 1885. Serial No. 170,500. (No model.)

To all whom it may concern:

Be it known that I, JOSEPH LOEWENTHAL, a citizen of the United States, residing at Newark, in the county of Essex and State of New Jersey, have invented certain new and useful Improvements in Coats and like Garments; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to adapt a coat or other similar garment to be used with propriety either as a dress-coat or for working purposes, and to furnish a double garment of equal elegance of fit and make on both sides.

The invention consists in the arrangements and combinations of parts, substantially as will be hereinafter set forth, and finally embodied in the clauses of the claims.

Referring to the two sheets of drawings, in which like letters indicate corresponding parts in each of the several figures, Figure 1, Sheet 1, is a perspective view of the improved garment. Fig. 2 is a section thereof taken on line *x* through the pocket. Fig. 3 is a section through line *y*. Fig. 4^a is a section on line *z* through the seam joining the sleeve to the body of the garment. Fig. 4^b is the same section, showing, however, the thicknesses of cloth in position for sewing. Fig. 5 is a section through lines *z'* and *z''*. Fig. 6 is a plan of the fly of the garment, showing an arrangement of buttons and button-holes. Fig. 7 is a section thereof through line *w*. Figs. 8 and 9 illustrate modifications in the construction of said fly. Fig. 10, Sheet 2, is a plan of a pattern of or one of a series of front pieces of the coat. Fig. 11 is a plan of a pattern of or one of a series of back pieces, the front and back pieces forming the body of the coat. Fig. 12 is a plan of a pattern of or one of a series of front sleeve-pieces. Fig. 13 is a plan of a pattern of or one of a series of back sleeve-pieces, and Fig. 14 is a plan of a pattern of or one of a series of collar-pieces.

In carrying out the invention, I provide four front pieces, *c*, Figs. 1 and 10. These in the completed coat lie in pairs on each side of the usual center opening down the front of the coat

or garment. Of the pairs the inner and outer thicknesses are exactly of the same size and shape, being cut together, but are preferably of differing qualities or colors.

d are back pieces, which are arranged in pairs on each side of a central back seam. When the coat is without this central seam, but one pair of back pieces are employed. In like manner the individual pieces of these pairs are alike in size and shape. I also provide upper sleeve-pieces, *e*, under sleeve-pieces, *f*, and collar-pieces *g*, which lie in pairs in their respective positions in the coat, the individual pieces of the pairs being alike in cut and size. When said parts are sewed together and form a completed garment, the seams of one layer or portion of the garment lie over or parallel with those of the other layer of said garment, and by this construction the smoothness and set of the outer layer will not be effected by seams of the inner or under layer crossing the unseamed portion of the cloth thereof, as will be understood.

In forming the coat I cut pocket openings or entrances in the front pieces, *C C*, which lie in the same relative positions in both of the layers, and sew with a plain seam welts *g* to the lower edges of said openings. I then arrange between the layers or thicknesses, in proper position, stays *m' m'*, which extend from points beneath the ends of the welts *g* to the edge of the coat in one direction and to the arm or sleeve seam in the other, and thus prevent the pockets from sagging. (See Figs. 1 and 10.) After sewing the welts to the edge of the opening and pressing the seam I arrange the silicia or other pocket material in place at the side of one of the welts, Fig. 2, to join the upper edge of said welt, as at *n*, to one edge of the pocket material by suitable stitching, then stitch, by a second line of stitching, the body material, the welt, and the pocket material together, as shown at *p*. It is evident that by turning the coat as described the half-finished pocket will meet the half-finished welt. These are finished in the manner set forth in describing the first portion of the pocket. After completing this portion of the pocket we join the upper edges, *O O*, of the cut or opening in the body material, which body material extends a short distance down into the pocket, forming a guide for the hand,

which prevents the hand from passing entirely through the garment, instead of into the pocket. I then tack the ends of the welt to the body of the garment, the stitches passing entirely through the ends of both the welts, the stays, the pocket material, and the body material, as indicated in Fig. 3, thus completing the pocket. I then double up the silicia or pocket material and sew the edges thereof to form the pocket, leaving the upper portion, facing or lining the welt, loose. In like manner I finish or partly finish the other pockets. I then join the different parts of the body-pieces, the stitches that join the parts *c* and *d* at the shoulder-seam *i* and at the sides *m m* not passing through from side to side of the coat, which would cause the coat to draw when turned, but only joining the inner thicknesses and the outer thickness, respectively, together, as shown in Fig. 5. The collar-pieces are joined together and to the body portions in like manner. The thicknesses or layers of the coat are next joined together at their outer edges, *h*, by first placing the said body-layers one exactly over the other and sewing the same all around, after which the coat is turned inside out through the unstitched portion at the armhole, after which the edge is finished by stitching.

30 After finishing the pockets, the sleeve-sections are prepared to be attached to the coat, as follows: The upper and under sections of one layer of the sleeves are sewed together at both seams. In the other layer the sections are sewed at the elbow-seam only. The sleeves are then placed to the body in the ordinary manner and sewed entirely through the four thicknesses, as in Fig. 4°, after which the remaining sleeve-seam is sewed. The inner and outer layers of the sleeve are then brought together, as in Fig. 4°, so that the rough edges are concealed; and, finally, the lower end edges of said sleeve are turned in a regular seam's width and stitched together in harmony with the other edges of the coat.

I do not wish to be understood as limiting myself to all the exact operations herein detailed. Thus constructed, the coat can be turned and used with either side out without any danger of the layers drawing or wrinkling or otherwise becoming unsightly, and at the same time the coat is better adapted to resist wear than other reversible or double coats, and, because of the uniformity of many of the pieces, the labor of cutting the parts is greatly reduced, as they may be cut by one operation.

I also provide a concealed or invisible fly, which enables me to use buttons on both sides of the garment, and to conceal one or both of them. As already stated, this fly is shown in Figs. 6, 7, 8, and 9. In these figures, *q* represents the invisible fly having the buttons *q' q'*, and *p p* show the thickness of goods on

each side, through which the button-holes are worked. As shown, one button, *q'*, is placed 65 on one side of the piece *q* and one upon the other. These buttons may be offset from each other on a horizontal line, as shown in Figs. 6 and 7, or on a vertical line, as shown in Fig. 8; or they may lie back to back, as shown in Fig. 9, in which latter case they sustain each other, and the pull or strain upon one in one direction is overcome by the pull or strain upon the other in the opposite direction as the coat is reversed. By means of this invisible fly, when the coat is reversed from one side to the other, one or the other of the buttons may be placed inside of the thickness of coat goods, and concealed as desired, while the button-hole, thus left free for use, 80 may be employed in engaging the exposed button on the opposite lappel of the coat.

Having thus described my invention, what I desire to claim and secure by Letters Patent is—

1. In a double jacket or coat, the combination of outer and inner sections or portions, the corresponding sections on each side being of the same size and shape and matching each other, and edge stitches and armpit-strokes 90 uniting both the inner and outer sections or portions at these points, substantially as set forth.

2. A double garment made of outer and inner sections, the corresponding sections on 95 both sides being of the same size and shape, and provided with pockets secured to the corresponding sections of both sides, with facings on both sides and welts tacked through both sections or thicknesses of the garment, whereby the pocket is equally accessible from either side and will draw equally upon both sides.

3. A coat or jacket having a concealed fly, as described, secured between the opposite sides or facings thereof, and provided with a 105 button on each side of the fly and a button-hole in each side or facing, substantially as and for the purpose set forth.

4. In a double garment having pockets lying between the two thicknesses of goods and having facings on both sides, the combination, with said thicknesses of goods and with said pockets and facings, of the stay-pieces *m' m'*, united to the corners of the pockets and extending between the thicknesses of goods to 115 the edges and armpits, respectively, and united thereto, so that the strain of pockets shall come upon these points and prevent the bagging of the garment.

In testimony that I claim the foregoing I have hereunto set my hand this 30th day of June, 1885.

JOSEPH LOEWENTHAL.
